US0D1066302S

(12) **United States Design Patent** (10) **Patent No.:** **US D1,066,302 S**
(45) **Date of Patent:** **** Mar. 11, 2025**

(54) **COMPONENT FOR A HEADPHONE**

(71) Applicant: **Apple Inc.**, Cupertino, CA (US)

(72) Inventors: **Jody Akana**, Los Altos Hills, CA (US); **Molly Anderson**, San Francisco, CA (US); **Bartley K. Andre**, Los Gatos, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, Cupertino, CA (US); **Abidur Rahman Chowdhury**, San Francisco, CA (US); **Clara Geneviève Marine Courtaigne**, Palo Alto, CA (US); **Markus Diebel**, San Francisco, CA (US); **Jonathan Gomez Garcia**, San Francisco, CA (US); **M. Evans Hankey**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Francisco, CA (US); **Joe Sung-Ho Tan**, Vienna (AT); **Clement Tissandier**, San Francisco, CA (US); **Eugene Antony Whang**, San Francisco, CA (US)

(73) Assignee: **Apple Inc.**, Cupertino, CA (US)

(**) Term: **15 Years**

(21) Appl. No.: **29/962,947**

(22) Filed: **Sep. 13, 2024**

Related U.S. Application Data

(63) Continuation of application No. 29/863,799, filed on Dec. 22, 2022, now Pat. No. Des. 1,042,412, which is a continuation of application No. 29/839,452, filed on May 20, 2022, now Pat. No. Des. 973,629, which is

a continuation of application No. 29/739,075, filed on Jun. 22, 2020, now Pat. No. Des. 952,598.
